DESIGN FOR A SUIT

Samuel Zimmerman, New York, N. Y.

Application August 4, 1937, Serial No. 70,835

Term of patent 3½ years

To all whom it may concern:

Be it known that I, Samuel Zimmerman, a citizen of the United States of America, residing in Manhattan, county and State of New York, have invented a new, original, and ornamental Design for a Suit, of which the following is a specification, reference being had to the accompanying drawing, forming part thereof, wherein,

Figure 1 is a front view of a suit showing my new design.

Figure 2 is a rear view of the suit shown in Figure 1.

The characteristic feature of my design resides in the combination on the suit disclosed of the diagonally arranged stitchings radiating from the outer edges of the curved pocket, and having seams beginning at the upper end of the curved pocket and converging toward the waistline, terminating outwardly at the lower end of the jacket.

I claim:

The ornamental design for a suit, substantially as shown and described.

SAMUEL ZIMMERMAN.
